MANUFACTURE OF ARTIFICIAL SILK

Antonie Jacobus Engel, Arnhem, Netherlands,
assignor to American Enka Corporation, Enka,
N. C., a corporation of Delaware

Application December 6, 1935, Serial No. 53,254
In the Netherlands December 8, 1934

8 Claims. (Cl. 242—43)

This invention relates to traverse mechanism of the type generally used in the production of bobbins and more particularly to means for forming the tapered winding on the end of the bobbin spools.

When winding textile materials, particularly artificial silk, as is known, a traverse varying device is employed by means of which the material obtained from the spinning process is guided so as to be deposited on bobbin spools in a predetermined form. Traverse mechanisms have been employed heretofore which give the winding on the end of the spool a conical shape, but these have not proved to be satisfactory because of the difference in density between the end edges of the winding and the main body portion thereof. Spools or bobbins formed in this manner cannot be washed, dyed, or dried evenly.

When winding bobbins with freshly spun rayon the traverse movements most generally used are almost always made up of one main movement combined with one or two auxiliary movements. The main movement being that obtained by allowing the roller of the thread guide arm to roll around the periphery of a cam of predetermined shape. The auxiliary movements employed are, first, the simple stroke displacement and the regular stroke shortening movement that takes place during the spinning period, and secondly, the "Pilgrim Step". These movements are distinguished one from the other by the ratio between the number of rotations of the auxiliary movements and the rotations of the main movement. When using the stroke shortening movement as referred to above, then during the entire winding on period the auxiliary movement moves only once causing the amplitude of traverse to change from a maximum in starting the winding on period to a minimum on the completion of the winding on period. Then when the "Pilgrim Step" is employed the auxiliary movement may make twenty times as many rotations as the main movement thereby causing the guide to oscillate backward and forward in its path across the spool or bobbin a corresponding number of times. Using the stroke displacement movement the auxiliary movement may turn as much as one twentieth the speed of the main movement thereby causing the amplitude of traverse to decrease to a minimum and build up to a maximum during 20 cycles of the guide.

In winding yarn into packages the effect of the auxiliary movement is to form packages

having a frusto-conical shape. However, the form of the spool or bobbin ends does not depend upon the number of rotations of the auxiliary movement but exclusively upon the speed pattern of the auxiliary movement.

Therefore, an object of this invention is the provision of mechanism whereby thread can be wound upon bobbins to form a package having end edges thick enough for proper washing, dyeing, or drying.

This invention also contemplates apparatus whereby a spool or package of thread is formed which will be free from noticeable ridges.

This invention further contemplates the provision of a mechanism whereby a number of the above described movements may be combined to give the desired type of winding.

Other objects, advantages and characteristic features of the invention will become apparent as the description of the disclosed embodiment progresses, reference being had to the annexed drawings in which:

Figs. 1, 2 and 3 are diagrammatic representations of fragmentary longitudinal sections of cylindrical windings showing the different effects produced in forming the winding with different arrangement of traverse mechanism;

Fig. 4 is a diagrammatic illustration of the traverse guide as taught by this invention showing the position of the cams while effecting maximum displacement of the thread guide to the right;

Fig. 5 is similar to Fig. 4 but showing the thread guide at its maximum displacement to the left;

Fig. 6 is a front detail elevation of the traverse mechanism;

Fig. 7 is a detail vertical longitudinal section along the line 7—7 of Fig. 6 showing the gear train employed in driving the auxiliary cam;

Fig. 8 is a vertical section of a modification of the gear train shown in Fig. 7, showing the use of a different gear ratio;

Fig. 9 is a vertical section of a second modification of the auxiliary cam driving mechanism.

Referring to the drawings, particularly Figs. 6 and 7, the mechanism is driven by a main drive shaft 10 that is connected to a suitable source of power not shown. A hub 11 is fitted on the opposite end of shaft 10 and adapted to turn with the shaft to drive the main eccentric or cam 12. Eccentric 12 is substantially heart-shaped in form and the periphery thereof serves as a track on which the roller end of a bell crank, which serves as the thread guide arm, is adapted to

move. The eccentric 12 is secured to a guide member 13 which is adapted to move in a line which is at right angles to the shaft. Provisions for such movement are made by 5 slotting member 13 as shown at 14 and 15 to receive the driving crank pin 16 and the hub 11 respectively. The crank pin 16 is secured to a crank arm 17 which is made integral with hub 11, by means of a bolt 18. Such an arrangement 10 is provided to permit the main cam 12 to move along its center line i. e., its line of symmetry, with respect to the main drive shaft 10. Springs 19 are connected to hub 11 and the cam 12 and thereby normally tend to force the point of cam 15 12 toward the main shaft 10. This movement, however, is limited by roller 29 that is mounted upon the guide member 13 by means of bolt 21. A second or auxiliary cam or eccentric member 20, the periphery of which forms the path for 20 roller 20, governs the movement of the main cam with respect to the shaft. Thus it can be readily seen that although the main cam 12 is adapted to slide on the shaft along its center line, it is also caused to rotate by the shaft. Cam 22 is 25 keyed to and adapted to be driven by bushing 23. Bushing 23 is driven by means of gears 24, 25, 26 and 27 from the main shaft 10. These gears obviously may be given any desired ratio to obtain varying relative speeds between cam 22 and cam 30 12. As shown in Fig. 8 a gear ratio may be selected which will cause the cam 22 to be driven at a relatively higher speed than cam 12, while on the other hand should it be desirable to drive cam 22 at a somewhat lower speed than cam 12, 35 an arrangement of gears such as is shown in Fig. 9 may be employed. The gears 24-27 must have then e. g. 34, 34, 29 and 39 teeth respectively.

The form that the winding will take on the spool is directly dependent upon the speed pattern of cam 22. Therefore, the shape of cam 22 40 must be of such contours as will give the desired form to the winding. In operation if it is desired to employ the "Pilgrim Step" movement in winding a thread on a spool or bobbin the cam 22 must, of necessity, be driven at a higher speed than cam 12. This will effect an oscillatory movement of the thread guide arm which will cause the thread to move forward and backward a number of times corresponding to the ratio of 45 the speeds of the respective cams during each traverse of the spool or bobbin. It is to be understood that cam 22 will have the desired contours to effect a proper shape of winding. The "Pilgrim Step" movement may be accomplished 50 by utilizing a gear train such as that disclosed in Fig. 8, the gears 24-27 having for example respectively 45, 23, 45 and 23 teeth.

If it is desired to wind the bobbins by the stroke shortening movement, then, of necessity, cam 22 55 must be driven at a much slower speed than cam 12. A gear train such as shown in Fig. 7 may be employed to effect this movement, the number of teeth of gears 24-27 being respectively 151, 150, 149 and 150. Driving cam 22 slower than cam 12 will cause the thread guide arm to move through a path traversing the spool from maximum amplitude or the longest stroke to an amplitude which approaches zero as a limit or the minimum stroke in the first 180° movement of 60 cam 22. As cam 22 completes one revolution or the second 180° the amplitude of traverse of the thread guide will increase to a maximum. Regardless of the number of revolutions made by the cam 22 relative to the cam 12 the shape of 70 cam 22

and may only be altered by changing the contours of cam 22.

Heart-shaped cams mounted and adapted to turn on eccentric bushings have been used heretofore on traverse mechanisms. In operation the 5 cam is driven at a constant speed while the eccentric bushing is rotated at any desired speed depending upon the form of movement that is to be employed in forming the winding. First let us suppose that the bushing turns very slow as 10 compared to the main cam, for example, no more than 180° per "wind on". Then, the cam will move with respect to the driving shaft in such a way that during the winding on period the stroke of the cam decreases regularly. The 15 eccentric bushing thus determines the speed at which the stroke will decrease and if it is assumed that the relative rotation of the eccentric bushing as compared to the cam is of a uniform speed, then it follows that the displacement of 20 the cam during the beginning of the winding on period takes place very slowly. However, during the winding on period it will increase, then toward the middle of this period, the speed of displacement will reach a maximum. Thereafter 25 the speed of displacement will decrease and toward the end of the winding on period will approach zero as a limit. Thus it can be seen that the speed pattern of displacement will assume the 30 form of a sine curve. In this case the frustoconical ends of the spool package will appear as indicated in Fig. 1 by the heavy line.

Alterations in the relative speed of the cam and bushing will not change the theoretical form of the spool end. When the eccentric bushing is 35 turned 360° instead of 180° relative to the cam during one winding on period the stroke is as indicated above throughout the first part of the period, but twice as fast. The package thus formed up to this point will only have one-half 40 the thickness of that discussed above. However, during the movement of the eccentric bushing through the remaining 180° of the winding on period the stroke will increase again and the movements will be exactly opposite to the ones 45 in the first half. The changes of the stroke are equal, but opposite, consequently the package is built up exactly as in the first instance. In either case the package retains the same form regardless of whether the eccentric bushing makes 50 one revolution or many relative to the cam. So Fig. 1 illustrates also the form of the spool or package formed by the simple stroke displacement or "Pilgrim Step" traverse produced by the auxiliary movement derived from the eccentric 55 bushing in the cam.

Due to the fact that the thread lags on making the return stroke relative to the thread guide, one does not get the theoretical form of spool end. The lagging of the thread relative to the guide 60 on returns will result in an extra turn of yarn being deposited on all points of the return and with a given number of returns these surplus turns will amount to a substantial quantity of yarn. It can readily be seen that whenever the 65 change in the length of stroke is small there will be a greater number of reverses that will come together and the amount of yarn built up as a result of the lag will increase accordingly. In Fig. 1 a dotted line illustrates how the shape of 70 the end of the spool is changed by this phenomenon and further explains how ridges in the winding originate.

Another auxiliary movement that has been proposed for reducing the stroke is one which effects 75

a constant speed displacement of a main cam along a line at right angles to the axis of rotation. A spool produced when utilizing this movement is of the form, theoretically, as illustrated by the full lines in Fig. 2. The lagging of the thread, however, will cause the shape of the spool to assume a form such as is indicated by dotted line in this same figure. Although the ridges are much smaller than those illustrated in Fig. 1 in dotted line, they are, nevertheless, of substantial size and, of course, are objectionable. Other difficulties encountered in using such a movement are, that the winding on the end of the spool is too thin and introduces difficulties when subjected to suction or pressure wash due to the fact that the permeability of the end of the winding is so much greater than that of the mid-section.

A spool or package of thread formed by utilizing the mechanism and method set out herein may have a form such as is illustrated by Fig. 3 i. e. the sectional contour of the end of the winding can be of a form corresponding to a logarithmic curve. This form has the advantage, that it gives an even permeability in pressure- or suction-washing and that it is free of ridges. This is possible because the thread lags when it reverses and a crossing different from that in the cylindrical part results, thereby effecting a lesser degree of permeability per unit thickness of package, which provides the necessary equalizing factor. The varying of the thickness after a logarithmic curve is obtained by making the speed of the auxiliary motion for stroke reduction increase regularly from the beginning to the end of the wind on period. The constructions here-to known can not give such a form, as they have not the characteristic of my invention, that the two traverse movements are combined in such a way that the auxiliary movement is employed only to move the main cam or eccentric member in its position relative to the shaft, while in each position this main cam alone determines the length of the stroke. So the form of the auxiliary cam can be chosen freely, as at any moment only one point of it is working.

The shape of the extreme ends of the spool is only affected by the change in shape of the auxiliary cam in the vicinity of the point which has the greatest radius, and that portion of the spool end defined by the extreme outer end of the spool and the cylindrical portion thereof is dependent for its shape on the shape of the auxiliary cam in the vicinity of its smallest radius. Therefore, it is obvious that regardless of the movement employed any desired shape of winding can be obtained by the selection of an auxiliary cam having the desired contours.

The position of the thread guide has been diagrammatically indicated in Figs. 4 and 5 for maximum strokes. Its position is definable in one extreme position by the dimension "A" of the main cam plus dimension "a" of the auxiliary cam and in the other extreme position by "B" minus "a". Therefore, the total stroke is "(A" plus "a") minus ("B" minus "a") and is equal to "A" minus "B" plus 2 "a". Minimum stroke may be obtained by rotating the auxiliary cam 180° (see Figures 4 and 5). In this case the roller is then closer to the shaft and the stroke is "A" minus "B" plus 2 "b".

The operation of the apparatus will be readily apparent from the foregoing description. During rotation of the drive shaft 10, the main heart-shaped cam 12 and the auxiliary cam 22 will be

driven in the same direction at uniformly different speeds by reason of the gears 24, 25, 26 and 27 which transmit power from the shaft 10, with which the main cam is operatively connected, to the bushing 23, to which latter the auxiliary cam is keyed. The main cam 12 is thus free to move in a line corresponding to its line of symmetry—that is, in a line which bisects the cam into two symmetrical parts—and is held by springs 19 in contact with the auxiliary cam 22. Therefore, the displacement of the roller riding upon the periphery of the main cam and controlling the traverse mechanism will be the resultant of two different movements of the main cam, namely, the displacement imparted to the roller by the throw of the main cam rotating about the axis of drive shaft 10, and the displacement resulting from shifting of the main cam along its line of symmetry under the influence of the auxiliary cam.

The main cam being heart-shaped, the shape of the auxiliary cam is preferably so selected that the main cam moves smoothly along its line of symmetry between its two extremes of travel with a speed of movement that increases with a decrease in the distance between the highest point of the main cam and its axis of rotation, and vice versa. Also the auxiliary cam is so formed that the cam throws of successive points of its periphery vary in accordance with a logarithmic curve.

In this way the thread guide carried by the traverse mechanism travels back and forth along the spool or bobbin with the speed of the auxiliary motion imparted by the auxiliary cam regularly increasing during the period of the shortening of the stroke of the thread guide. This results in a package having the general form indicated in Fig. 3 in which the end edges are substantially free from ridges and are of a suitable density for proper washing, dyeing and drying. While the invention in its preferred form contemplates the employment of an auxiliary cam of the logarithmic character described above, it will be apparent that in its broadest aspect the invention is not limited to any particular shape of auxiliary cam, and that the shape of such cam may be suitably selected according to the desired form of the package to be wound.

Although for purpose of illustration and explanation this invention has been described in connection with a thread guide that is fastened to the end of a swinging lever of the bell crank type, the invention is equally applicable to the reciprocating form of guide member. In fact, it would find application to substantially all forms of traverse mechanisms employed in the spinning art.

"Permeability" as used herein is defined as that quantity of water which will flow through one square centimeter of the surface of the package at a given pressure in a given interval of time, while "wind on" or "winding on" period, as used herein, refers to a period in which the spool or package is completely wound.

What I claim is:

1. In an apparatus for winding spools or bobbins, a traverse actuating mechanism comprising a main cam of symmetrical shape and adapted to control the thread guide arm of the traverse mechanism, an auxiliary cam located adjacent the main cam and independently rotatable with respect thereto, means supporting the main cam for displacement along its line of symmetry, means extending between the main cam and auxiliary cam whereby relative rotation between the

- cams causes displacement of the main cam along its line of symmetry and means for rotating the cams at relatively different speeds.
2. In an apparatus for winding spools or bobbins, a traverse actuating mechanism comprising a main cam of symmetrical shape and adapted to control the thread guide arm of the traverse mechanism, an auxiliary cam located adjacent the main cam and independently rotatable with respect thereto, a roller supported by the auxiliary cam, means yieldingly retaining the roller in engagement with the periphery of the auxiliary cam whereby relative rotation between the cams causes displacement of the main cam along its line of symmetry and means for rotating the cams at relatively different speeds.
3. In an apparatus for winding spools or bobbins, a traverse actuating mechanism comprising a rotary drive shaft, a main cam operatively connected for rotation to the drive shaft, said main cam being of symmetrical shape and adapted to control the thread guide arm of the traverse mechanism, an auxiliary cam located in closely spaced parallel relation to the main cam and independently rotatable with respect thereto, means supporting the main cam for displacement along its line of symmetry, means extending between the main cam and auxiliary cam whereby relative rotation between the cams causes displacement of the main cam along its line of symmetry and means for rotating the drive shaft and auxiliary cam.
4. In an apparatus for winding spools or bobbins, a traverse actuating mechanism comprising a rotary drive shaft, a main cam operatively connected for rotation to the drive shaft, said main cam being of symmetrical shape and adapted to control the thread guide arm of the traverse mechanism, an auxiliary cam located in closely spaced parallel relation to the main cam and independently rotatable with respect thereto about an axis corresponding to the axis of said drive shaft, means supporting the main cam for displacement along its line of symmetry, means extending from the main cam and yieldingly maintained in engagement with the periphery of the auxiliary cam whereby relative rotation between the cams causes displacement of the main cam along its line of symmetry and means for rotating the drive shaft and auxiliary cam at relatively different speeds.
5. In an apparatus for winding spools or bobbins, a traverse actuating mechanism comprising a rotary drive shaft, a main cam operatively connected for rotation to the drive shaft, said main cam being of symmetrical shape and adapted to control the thread guide arm of the traverse mechanism, an auxiliary cam located in closely spaced parallel relation to the main cam and independently rotatable with respect thereto, means supporting the main cam for displacement along its line of symmetry, means extending between the main cam and auxiliary cam whereby relative rotation between the cams causes displacement of the main cam along its line of symmetry, means for rotating the drive shaft and speed change mechanism operatively connected to the drive shaft for rotating the auxiliary cam at a different speed relative to the drive shaft.
6. In an apparatus for winding spools or bobbins, a traverse actuating mechanism comprising a main cam of symmetrical shape and adapted to control the thread guide arm of the traverse mechanism, an auxiliary cam located adjacent the main cam and independently rotatable with respect thereto, means supporting the main cam for displacement along its line of symmetry, means extending between the main cam and auxiliary cam whereby relative rotation between the cams causes displacement of the main cam along its line of symmetry, said auxiliary cam being so shaped that the cam throws of successive points upon its periphery vary in accordance with a logarithmic curve, and means for rotating the cams at relatively different speeds.
7. In an apparatus for winding spools or bobbins, a traverse actuating mechanism comprising a rotary drive shaft, a hub fixed to the drive shaft and having a crank arm extending radially therefrom, a main cam of symmetrical shape loosely associated with the hub, and adapted to control the thread guide of the traverse mechanism, a guide member rigidly fixed to the main cam and having an elongated slot therein disposed parallel to the line of symmetry of the main cam, a pin extending laterally from the crank arm and receivable in the slot for imparting rotation to the guide member and main cam, a bushing surrounding the drive shaft and independently rotatable with respect thereto, an auxiliary cam fixed to said bushing and located adjacent the guide member, a roller carried by said guide member, spring means yieldingly urging said roller into engagement with the periphery of the auxiliary cam whereby relative rotation between the cams causes displacement of the main cam along its line of symmetry, and means for rotating the drive shaft and bushing at different speeds.
8. A traverse actuating mechanism as set forth in claim 7 in which the auxiliary cam is so shaped that the cam throws of successive points upon its periphery vary in accordance with a logarithmic curve.

ANTONIE JACOBUS ENGEL.
